UNITED STATES PATENT OFFICE.

BENJAMIN F. CAHN, OF CINCINNATI, OHIO.

DESIGN FOR A WALL-FIXTURE FOR COUNTERS.

SPECIFICATION forming part of Design No. 22,580, dated July 4, 1893.

Application filed June 8, 1893. Serial No. 477,019. Term of patent 3½ years.

To all whom it may concern:

Be it known that I, BENJAMIN F. CAHN, a citizen of the United States, and a resident of Cincinnati, in the county of Hamilton and State of Ohio, have invented a certain new and useful Design for Wall-Fixtures for Counters, of which the following is a specification.

My invention is a new and original design for wall fixtures for counters, the main features of which are the closet or pedestal with its forwardly projecting drawer portion, the back with the entablature above it, and the forwardly projecting cornice or canopy supported by columns which rest upon the top of the closet portion, as shown in the accompanying drawings, in which—

Figure 1 is a front elevation of one half of a fixture made according to my new design, with a portion of the canopy broken away to expose the arched reflecting panels forming the upper part of the back of the fixture. Fig. 2 is a central transverse vertical sectional view of the same.

Referring to the parts by letter, A is the closet or side board with its center formed of a diamond shaped bevel edged reflecting panel a, having in either corner spandrels a', which are triangular bevel edged reflecting panels, and on either side of this center ornamentation are four arched bevel edged reflecting panels a² surrounded with plain moldings. Above these panels and apparently supported by the fluted pilasters A' having carved Ionic capitals a³, is the drawer portion A², projecting slightly forward, its lower edge enriched with a bead molding a⁴ and its front ornamentation consisting of plain bevel edged rectangular panels a⁵, except above each pilaster, where the plainness is broken by carved sunken panels a⁶. Resting upon the rear closet portion is the back, which has almost its entire surface composed of mirrors, the center one B, being rectangular, while those at each end B' are bevel edged and have rounded corners, and all are surrounded by a rich bead molding. At either side of the center mirror is a column B² with plain shaft b and surmounted by a bulb shaped carved capital b' and at each end of the back rises a fluted column B³, whose capital b² is profusely

inner beaded portions d⁴ of the end capitals d extend backwardly to the wall fixture, except the upper portions, which are intercepted by the front of the canopy, as seen in Fig. 2.

The effect of the design may be heightened by electric jets suspended from the roof of the canopy and placed in such position that the light may be reflected by the number of reflecting panels which form the back and

ornamented with carved foliage. Above the mirrors and seemingly resting upon the columns B² and B³, is the top B⁴ of the back fixture, which is enriched with small arched mirrors b⁵. The base of the architrave is a molding which is returned over each capital to form its abacus. The molding is corbelled by molded dentals b⁶, and immediately above them and between the arched panels are fluted pilasters.

A distinguishing feature of my design is the overhanging canopy like portion C. The molded cornice C' has its lower edge finished with a continuous row of dentals and forms the upper part of the canopy. Beneath the cornice is a frieze C² fitted with bevel edged reflecting mirrors of various sizes and shapes. At each end the oval reflecting panel c has at either side the mirrors c', having their upper and lower edges and one end formed in straight lines, while the opposite ends are formed concentric to the ends of the panel c. The center of the frieze follows the same design, and the panels between these end and center reflecting panels are rectangular. The ovolو molding c², with the plain molding beneath it, edges the canopy proper, which is supported by four columns resting upon the closet portion. Of these the end columns or supports, D, extend back and close the ends of the fixture, and on the front and two sides are ornamented with nodules, around which twines a carved vine. Surmounting this column is a heavily carved capital d, representing the head of an animal, conventionally treated. The intermediate columns D' have their capitals d' arched outwardly upon each side to meet the edge of the cornice. The front of the capital has carved upon it a head, from either side of which carved foliage reaches almost to the top of the capital. Immediately above this carved head, and extending over the molding, frieze and cornice of the canopy, is a carved shield d² with carved foliage taking the form of a scroll, springing from either side, and the top in front of the cornice molding terminates in a conventional shell.

The curved underside of the cap d' is fitted with reflecting panels d³, as seen in Fig. 2. The

canopy of the fixture and the reflecting panels d³ of the arched capitals.

What I claim as new, and desire to secure by Letters Patent, is—

The design for wall fixtures for counters, substantially as herein shown and described.

BENJAMIN F. CAHN.
